TOGGLE MECHANISM FOR JAW-TYPE CRUSHER

Samuel W. Traylor, Jr., Allentown, Pa.

Application August 3, 1953, Serial No. 371,992

9 Claims. (Cl. 241—269)

The present invention relates to jaw-type crushers and 15 more particularly to a novel toggle mechanism for crushers of this type.

In jaw-type crushers a swing jaw is mounted for swinging movement to and from a fixed jaw. There are two major constructions for effecting the swinging movement 20 of the jaw. In the first construction, the so-called Blake jaw crusher, the swing jaw is pivotally mounted on a fixed shaft, and the swinging movement is effected by a toggle mechanism having two flat toggle plates in endwise compression between a vertically reciprocating pitman, and the swing jaw and the frame respectively. In the other construction, the so-called eccentric-in-jaw crusher, the swing jaw depends from a driven eccentric shaft, and horizontal movement is imparted to the lower end of the swing jaw by a flat toggle plate held in endwise compression between the frame and the swing jaw.

In each construction, the conventional toggle mechanism is subject to substantial compressive forces. In addition to the purely compressive forces, the toggle plates are subject to torsional or twisting forces when there is a greater load at one end of the swing jaw than at the other. The greater load may be caused by a larger quantity of material at the one end, or it may be caused by the presence of tramp iron or other uncrushable objects at one end of the jaw. In any event, the uneven loading of the swing jaw exerts a torsional force on the conventional toggle mechanism and causes uneven wear in the crusher mechanism. On occasions, the uneven load may even tend to distort the frame and cause excessive strains therein. As a result, conventional jaw crushers necessarily must be made excessively strong and heavy to avoid the adverse effects of uneven loading.

With the foregoing in mind, a primary object of the present invention is to provide a novel toggle mechanism for a jaw-type crusher which minimizes the torsional or twisting stresses in the mechanism.

A further object of the present invention is to provide a toggle mechanism which is self-adjusting to balance out uneven loads on the jaw, and enable the parts to be made substantially smaller and lighter than in conventional apparatus.

These and other objects of the invention and the various features and details of the construction and operation thereof are more fully set forth hereinafter with reference to the accompanying drawings in which:

Fig. 1 is a plan view of a Blake-type jaw crusher, made in accordance with the present invention;

Fig. 2 is a side elevational view partially in section of the crusher illustrated in Fig. 1;

Fig. 3 is an enlarged sectional view taken on the line 3—3 of Fig. 1;

Fig. 4 is a fragmentary horizontal sectional view showing the arrangement of the novel toggle mechanism made in accordance with the present invention;

Fig. 5 is a vertical sectional view of an eccentric-in-jaw-type crusher made in accordance with the present invention; and,

Fig. 6 is a horizontal sectional view taken on the line 6—6 of Fig. 5.

The present invention provides a novel toggle mechanism for jaw-type crushers wherein a plurality of generally cylindrical struts or toggle members replace the conventional toggle plates. The struts operate to balance out the effects of an uneven load on the swing jaw of the crusher.

Referring now to the drawings, Figs. 1 to 4 thereof 10 illustrate the invention as applied to a Blake type of crusher comprising a frame 10 having a fixed jaw plate 11 rigidly secured to one side thereof, a swing jaw 12 pivotally mounted on a shaft 13 fixed in the frame 10, a toggle mechanism 14 disposed between the swing jaw 12 and the opposite side of the frame 10, and a pitman 15 engaging the toggle mechanism and mounted for vertical reciprocation by a driven eccentric shaft 16.

In accordance with the present invention, the toggle mechanism 14 comprises a distributor 20 resiliently held against the lower surface of the pitman 15 by a spring-loaded bolt 21. A plurality of struts or toggle members, in the present instance four, 22, 23, 24, and 25 are engaged against the distributor and held against lateral displacement therein by replaceable wear socket members 26. The forward struts or toggle members 22 and 23 engage against the swing jaw 12 which has wear socket members 27 similar to the wear members 26 in the distributor. The rear toggle members 24 and 25 engage in wear members 34 in a toggle block 28 which is held against displacement of the frame by a pair of bolts 29 and a toggle block wedge 30. The bolts 29 are engaged in elongated slots 31 in the frame so that the block 28 may be adjusted forward and back on the frame to compensate for wear and to make minor adjustments in the size of the cavity between the swing jaw 12 and the fixed jaw plate 11. The wedge 30 is vertically adjustable by means of a bolt 32 to determine the fore and aft adjustment of the toggle block 28. A spring-loaded tension rod 33 biases the swing jaw rearwardly to maintain engagement of the toggle members 22 to 25 inclusive in their respective socket members.

In accordance with the invention, the distributor 20 is not rigidly fixed to the pitman 25 but is capable of slight angular movement as well as rotary movement thereon. 45 To this end, the upper portion of the distributor 20 is formed as a spherical dome as indicated at 35, and the dome portion is received in a spherical socket 36 to afford limited universal movement between the pitman and the distributor. Thus, the distributor is free to automatically align itself to balance out uneven loads on a swing jaw 12.

In the operation of the device, when an uneven load is exerted on the swing jaw 12, for example, opposite the toggle member 23 (see Fig. 4), the force is transmitted to the distributor 20 along the center line of the toggle member 23. Since the center line of the toggle member is out of alignment with the center of the distributor, the rearward force will be substantially balanced out by the rear toggle member 24, and the lateral force will be balanced out by the members 22 and 25. The forces in the struts 22 and 23 will therefore be equal to the forces in the struts 24 and 25. As a result of this balance between the forces, there will be relatively no twisting action on the jaw 12 and the toggle block 28. The greatest part of the forces exerted by the struts on each of the members 12 and 28 will be directed in opposition to one another so that any tendency of the members 12 and 28 to twist is substantially eliminated. Because of the novel construction of the pitman 15 and the distributor 20, all torsional forces upon the pitman and its shaft are eliminated which enables them to be made smaller and lighter, thereby saving weight and cost in the apparatus.

The invention is not limited to Blake-type jaw crush-

ers but may be utilized in eccentric-in-jaw-type crushers such as, for example, illustrated in Figs. 5 and 6. In this type of construction, the toggle plate which is in end-wise compression between the frame and the jaw, is replaced by a toggle mechanism somewhat similar to the mechanism described above in connection with Figs. 1 to 4. As seen in Fig. 5, the swing jaw 41 is mounted on a driven eccentric shaft 42 for swinging movement toward and from a fixed jaw 43 fixed on the frame 44 of the apparatus. The toggle mechanism, indicated generally at 45, is disposed between the lower end of the swing jaw and toggle blocks 46, 46. The toggle blocks are mounted for fore and aft adjustment by means of wedge members 47, 47 which are adjusted laterally by adjusting screws 48, 48. A spring-loaded tension rod 49 is provided to bias the swing jaw 41 rearwardly in the apparatus.

In accordance with the invention, the toggle mechanism 45 comprises a distributor 51 and a plurality of toggle members 52, 53, 54, and 55. Replaceable wear socket members 56 are provided in the distributor 51, the swing jaw 41 and the toggle block 46 to receive the swing jaw 41 and the toggle block 46 to receive the toggle members 52 to 55 inclusive. Under the bias of the spring-loaded tension rod 49, the distributor 51 is urged upwardly against a depending plate 58 rigidly secured to the framework as indicated at 59. The lower surface of the plate 58 and the upper surface of the distributor 51 are smooth for sliding engagement, permitting limited rotational movement of the distributor upon the application of an uneven load against the swing jaw 41. It is apparent that the toggle mechanism 45 functions identically to the toggle mechanism 14 to counterbalance the forces created by an uneven load against the swing jaw 41.

While particular embodiments of the invention have been herein illustrated and described, it is not intended to limit the invention to such disclosures, and changes and modifications may be made therein and thereto within the scope of the following claims.

I claim:

1. In a jaw-type crusher having a frame, a fixed jaw adjacent one end of said frame, and a depending swing jaw mounted on an axis substantially parallel to the fixed jaw for swinging movement toward and away from said fixed jaw, a toggle mechanism disposed between said swing jaw and the frame for effecting swinging movement of the swing jaw comprising a distributor, means limiting movement of said distributor in one vertical direction and affording rotary movement thereof in a substantially horizontal plane, at least two opposed elongated toggle members, each engaged at one end against said swing jaw, and inclined in said one vertical direction longitudinally and laterally of the frame into engagement at the opposite end against the distributor, at least two opposed elongated toggle members, each engaged at one end against the opposite end of the frame and inclined in said one vertical direction longitudinally and laterally of the frame into engagement at the opposite end against the distributor, and means biasing said swing jaw away from said fixed jaw to compress said toggle members and bias said distributor in said one vertical direction against said limit means.

2. In a jaw-type crusher having a frame, a fixed jaw adjacent one end of said frame and a depending swing jaw mounted on an axis substantially parallel to said fixed jaw for swinging movement toward and away from said fixed jaw, a toggle mechanism disposed between said swing jaw and the opposite end of the frame for effecting swinging movement of the swing jaw comprising a distributor, means limiting movement of said distributor in one vertical direction and affording rotary movement thereof in a substantially horizontal plane, at least two opposed generally cylindrical toggle members, each engaged at one end against said swing jaw, and inclined in said one vertical direction longitudinally and laterally

5 of the frame into engagement at the opposite end against the distributor, at least two opposed generally cylindrical toggle members, each engaged at one end against said opposite end of the frame and inclined in said one vertical direction longitudinally and laterally into engagement at the opposite end against the distributor, and means biasing said swing jaw away from the fixed jaw to compress said toggle members and bias said distributor in said one vertical direction against said limit means.

3. In a jaw-type crusher having a frame, a fixed jaw adjacent the forward end of said frame, and a depending swing jaw mounted on an axis substantially parallel to said fixed jaw for swinging movement toward and away from said fixed jaw, a toggle mechanism disposed between said swing jaw and the rear end portion of the frame for effecting swinging movement of the swing jaw comprising a distributor, means limiting movement of said distributor in one vertical direction and affording rotary movement thereof in a substantially horizontal plane, at least two opposed elongated forward toggle members each engaged at one end against the swing jaw and inclined in said one vertical direction rearwardly and laterally into engagement at the opposite end against the distributor, at least two elongated rearward toggle members each engaged at one end against said rear end portion of the frame and inclined in said one vertical direction forwardly and laterally into engagement at the opposite end against the distributor, means defining sockets in said swing jaw, distributor, and rear frame portion to receive the toggle members and support the same against lateral movement, and means biasing said swing jaw rearwardly away from said fixed jaw to compress the toggle members and bias said distributor in said one vertical direction against said limit means.

4. In a jaw-type crusher having a frame, a fixed jaw adjacent the forward end of said frame, and a depending swing jaw mounted on an axis substantially parallel to said fixed jaw for swinging movement toward and away from said fixed jaw, a toggle mechanism disposed between said swing jaw and the rear end portion of the frame for effecting swinging movement of the swing jaw comprising a distributor, means limiting movement of said distributor in one vertical direction and affording rotary movement thereof in a substantially horizontal plane, at least two opposed elongated forward toggle members each engaged at one end against the swing jaw and inclined in said one vertical direction rearwardly and laterally into engagement at the opposite end against the distributor, at least two elongated rearward toggle members each engaged at one end against said rear end portion of the frame and inclined in said one vertical direction forwardly and laterally into engagement at the opposite end against the distributor, means defining sockets in said swing jaw, distributor, and rear frame portion to receive the toggle members and support the same against lateral movement, and means biasing said swing jaw rearwardly away from said fixed jaw to compress the toggle members and bias said distributor in said one vertical direction against said limit means.

5. In a jaw-type crusher having a frame, a fixed jaw adjacent the forward end of said frame, and a depending swing jaw mounted on an axis substantially parallel to said fixed jaw for swinging movement toward and away from said fixed jaw, a toggle mechanism disposed between said swing jaw and the rear end portion of the frame for effecting swinging movement of the swing jaw comprising a distributor, means limiting movement of said distributor in one vertical direction and affording rotary movement thereof in a substantially horizontal plane about its center, at least two opposed elongated forward toggle members each engaged at one end against the swing jaw and inclined in said one vertical direction rearwardly and laterally into engagement at the opposite end

against the distributor, at least two elongated rearward toggle members each engaged at one end against said rear end portion of the frame and inclined in said one vertical direction forwardly and laterally into engagement at the opposite end against the distributor, the axis of each said toggle member being out of alignment with the center of said distributor, and means biasing said swing jaw rearwardly away from said fixed jaw to compress the toggle members and bias said distributor in said one vertical direction against said limit means.

6. In a jaw-type crusher having a frame, a fixed jaw adjacent the forward end of said frame, and a depending swing jaw mounted on an axis substantially parallel to said fixed jaw for swinging movement toward and away from said fixed jaw, a toggle mechanism disposed between said swing jaw and the rear end portion of the frame for effecting swinging movement of the swing jaw comprising a distributor, means limiting upward movement of said distributor and affording rotary movement thereof in a substantially horizontal plane about its center, at least two opposed elongated generally cylindrical forward toggle members each engaged at one end against the swing jaw and inclined upwardly, rearwardly and laterally into engagement at the opposite end against the distributor, at least two elongated generally cylindrical rearward toggle members each engaged at one end against said rear end portion of the frame and inclined upwardly, forwardly and laterally into engagement at the opposite end against the distributor, means defining sockets in said swing jaw, distributor, and rear frame portion to receive the toggle members and support the same against lateral movement, wear members positioned in said sockets between each said toggle and its sockets, the axis of each said toggle member being out of alignment with the center of said distributor and means biasing said swing jaw rearwardly away from said fixed jaw to compress the toggle members and bias said distributor upwardly against said limit means.

7. In a Blake-type jaw crusher having a frame, a fixed jaw adjacent one end of said frame, a depending swing jaw mounted on a fixed axis substantially parallel to the fixed jaw for swinging movement toward and away from said fixed jaw, a toggle mechanism disposed between said swing jaw and the opposite end of the frame for effecting swinging movement of the swing jaw comprising a distributor, a vertically reciprocating pitman resiliently mounting said distributor, limiting movement thereof in one substantially vertical direction and affording rotary movement thereof in a horizontal plane, at least two op-

posed elongated toggle members, each engaged at one end against said swing jaw, and inclined in said one vertical direction longitudinally and laterally of the frame into engagement at its opposite end against the distributor, at least two opposed elongated toggle members, each engaged at one end against the opposite end of the frame and inclined in said one vertical direction longitudinally and laterally of the frame into engagement at its opposite end against the distributor, and means biasing said swing jaw away from said fixed jaw to compress said toggle members and bias said distributor in said one vertical direction against said pitman.

8. A crusher according to claim 7 wherein said pitman is formed with a spherical socket, and said distributor is formed with a spherical dome to be received in said spherical socket to afford limited universal movement between said pitman and said distributor.

9. In an eccentric-in-jaw type crusher, having a frame, a fixed jaw adjacent one end of said frame, and a depending jaw mounted on an eccentric driven shaft substantially parallel to the fixed jaw for swinging movement toward and away from said fixed jaw, a toggle mechanism disposed between said swing jaw and the opposite end of the frame for effecting swinging movement of the swing jaw upon rotation of said eccentric shaft comprising a distributor, a limit plate mounted on said frame limiting movement of said distributor in one vertical direction and affording rotary movement thereof in a substantially horizontal plane, at least two opposed elongated toggle members, each engaged at one end against said swing jaw, and inclined in said one vertical direction longitudinally and laterally of the frame into engagement at the opposite end against the distributor, at least two opposed elongated toggle members, each engaged at one end against the opposite end of the frame and inclined in said one vertical direction longitudinally and laterally of the frame into engagement at the opposite end against the distributor, and means biasing said swing jaw away from said fixed jaw to compress said toggle members and bias said distributor in said one vertical direction against said limit plate.
